UNITED STATES PATENT OFFICE

132,532

DESIGN FOR A COMBINATION CABINET AND TABLE

Andrew W. Junkunc, Chicago, Ill.

Application March 2, 1942, Serial No. 106,049

Term of patent 14 years

To all whom it may concern:

Be it known that I, Andrew W. Junkunc, a citizen of the United States, residing at Chicago, in the county of Cook and State of Illinois, have invented a new, original, and ornamental Design for a Combination Cabinet and Table, of which the following is a specification, reference being had to the accompanying drawing, forming a part thereof.

In the drawing:

Fig. 1 is a perspective view of the combination cabinet and table, showing my design in its opened position.

Fig. 2 is a perspective view of the combination cabinet and table in its closed position and on a reduced scale; and

Fig. 3 is a top plan view thereof.

I claim:

The ornamental design for a combination cabinet and table, as shown.

ANDREW W. JUNKUNC.
